UNITED STATES PATENT OFFICE.

ANDREW D. SMITH, OF MARION, INDIANA.

HOT-AIR FURNACE.

1,207,646.

Specification of Letters Patent. Patented Dec. 5, 1916.

Application filed October 9, 1914. Serial No. 865,875.

To all whom it may concern:

Be it known that I, ANDREW D. SMITH, a citizen of the United States, residing at Marion, in the county of Grant and State 5 of Indiana, have invented new and useful Improvements in Hot-Air Furnaces, of which the following is a specification.

This invention relates to heating furnaces and has particular application to a hot air 10 furnace.

The object of this invention is to provide a device of this character which is a combined heating and ventilating apparatus for houses, dwelling or the like, wherein the 15 furnace is provided with improved means for ejecting pure heated air into the dwelling and for ejecting or withdrawing the bad air from the dwelling.

In the accompanying drawings: Figure 1 20 is partly an elevation and partly a sectional view of a furnace constructed in accordance with my invention and showing the same installed in a cellar and connected to a chimney or flue and provided with heating 25 pipes which lead to an overhead apartment. Fig. 2 is a vertical central sectional view of the same. Fig. 3 is a front elevation of the same. Fig. 4 is a vertical transverse sectional view through the furnace taken on 30 the line 4-4 of Fig. 1.

The furnace as here shown comprises a substantially rectangular-shaped fire box 1. A fire pot 2 is disposed within said casing in spaced relation with the top 35 and bottom thereof and from one of the ends of the casing, as indicated by the numeral 3. The fire pot is provided with the usual grate and has disposed beneath the same an ash pan 4. A substantially rec- 40 tangular casing 5 surrounds and completely houses the fire pot casing, the top wall 6 of the casing 5 being rounded and arranged in spaced relation to the fire pot casing, the said top coacting with the top wall 7 of the 45 fire pot casing to provide an air moistening chamber 8 extending the entire length of the casing, and with which between the ends of the casing communicate hot air distribut- 50 ing pipes 9 which communicate with apart- ments in the building which receive heated air from the furnace. The front end wall of the casing 5 is provided with the usual fuel door 10 and ash door 11 in which is 55 arranged a damper for regulating the draft of air through the furnace. The other end of the casing 5 coacts with a transversely

extending partition 12 within the fire pot casing to provide a smoke chamber 13 from which soot and other matter may be removed by means of a door 14 in one side 60 wall of the casing 5.

A smoke pipe 15 is arranged at the rear end of the furnace and provided with branches 16, 17 and 18, each of which is provided with a damper 19, the branch pipe 65 16 communicating with the air moistening chamber 8 near the top thereof, while the branch pipe 17 establishes communication with the smoke chamber 13 at its upper end and in alinement with the passage for the 70 products of combustion below the top 7 of the fire pot casing. The branch pipe 18 communicates with the lower end of the smoke passage 13.

The side walls of the casing 5 are held in 75 spaced relation with the side walls of the fire pot casing by means of vertically ex- tending and spaced partitions 20 and 21. The partitions 21 which are arranged adja- 80 cent the front of the casing receive and sup- port the convoluted heating pipes 22 ar- ranged upon opposite sides of the fire pot casing and between the same and the side 85 walls of the casing 5. The convolutions in the pipes 22 are arranged to extend longi- tudinally of the furnace, so that the upper ends of the pipes communicate with the air 90 moistening chamber 8 near the rear end of the furnace, while the lower ends of the pipes 22 are connected with a branch pipe 90 23 located beneath the front end of the fur- nace and connected with a cold air supply 95 duct 24 in which is arranged a damper 25 by means of which the amount of air pass- ing into the air heating pipes 22 may be 95 regulated.

In order that the air entering the air cham- 7 ber 8 from the pipes 22 may be moistened, a water tank 26 is supported by the top 7 of the fire pot casing at the forward end 100 of said chamber, said tank having an open top and a supply pipe 27 communicating therewith through the top 6 of the casing 5 and provided with a valve 28 by means 105 of which the flow of water through the pipe 27 may be controlled. The water gage 29 is connected with the water tank 26 and arranged upon the front of the furnace, so that the quantity of water within the tank 26 may be ascertained at all times. 110

As it has been found that certain diseases can be advantageously treated by diffusing

in heated air certain remedial agents, a funnel 29' is supported by the curved wall 6 of the casing 5 above the water tank 26, and through this funnel may be poured the agent with which it is desired to medicate the heated air, said funnel having a tightly fitting cap.

It will be understood that combustion is promoted in the furnace in the usual manner with the exception that when the fuel in the fire pot has burned a sufficient length of time to enable the greater portion of the gas and smoke therefrom to escape through the branch pipe 17 into the smoke pipe 15, the damper 19 is closed, and the damper 19 in the branch pipe 18 open, so that the heat rising from the fuel will remain longer in contact with the top 7 of the fire pot casing, thus reducing the quantity of fuel used in the furnace to heat the air passing into the pipes 22 through the cold air supply pipe 24 and branch pipe 23. When the air enters the chamber 8 from the pipes 22 it is sufficiently heated to absorb vapor given off from the water tank 26, and it will be noted that by spacing the water tank from the upper ends of the pipes 22 heated air entering the chamber 8 is caused by the curved top 6 of the casing 5 and the superheated air in the spaces between the partitions 20 and 21 to freely circulate and intermingle with the vapor before the heated air enters the distributing pipes 9. When it is desired to ventilate the apartments with which the air heating pipes 9 are connected by means of the furnace, the damper 25 in the cold air supply pipe 24 is closed, and the damper 19 in the branch pipe 16 open so that foul air within the apartments is drawn through the pipes 9 and escapes into the smoke flue 15 through the branch pipe 16.

It will be seen from the foregoing description that the water tank 26 which contains the medicated water to be vaporized is located at the forward end of the fur-

nace and in advance of the air distributing pipes 9, and that the branch pipe 16 communicates with the air chamber 8 at the upper end of said chamber, so that as the foul air is being drawn through the pipes 9 and into the smoke pipe 15, the greater quantity of the vapor rising from the tank 26 seeks the lower level in the chamber 8 and is prevented from being withdrawn with the foul air through the smoke flue.

From the above statements, it will be at once apparent that a furnace has been provided which not only heats and moistens the air which is distributed to the apartments of the building in which the furnace is installed, but that foul air may be removed from said apartments by means of the furnace.

Having thus described my invention, I claim:—

A furnace comprising a casing, an air chamber within the upper part of the casing, a smoke chamber within the lower part of the casing, a fire box within said casing and spaced from said air chamber and the rear wall of the smoke chamber, air pipes arranged upon opposite sides of the fire box and communicating with the air chamber at the rear end thereof, a smoke pipe in the rear of said casing and having its lower end communicating with the lower portion of the smoke chamber in the rear of the fire box, a branch pipe connecting said smoke pipe with the upper portion of the smoke chamber, a second branch pipe connecting the air chamber with the smoke pipe, dampers arranged within each of the smoke pipes, and distributing pipes communicating with said air chamber.

In testimony whereof I affix my signature in presence of two witnesses.

ANDREW D. SMITH.
